UNITED STATES PATENT OFFICE.

GRACE G. DRAYTON, OF NEW YORK, N. Y.

DESIGN FOR A TOY BANK OR SIMILAR ARTICLE.

47,221.

Specification for Design.

Patented Apr. 13, 1915.

Application filed December 31, 1914. Serial No. 879,972. Term of patent 3½ years.

To all whom it may concern:

Be it known that I, GRACE G. DRAYTON, a citizen of the United States, residing at New York, in the borough of Manhattan and State of New York, have invented a new, original, and ornamental Design for Toy Banks or Similar Articles, of which the following is a specification, reference being had to the accompanying drawing, forming part thereof.

I claim:

The ornamental design for a toy bank or similar article as shown.

GRACE G. DRAYTON.
